UNITED STATES PATENT OFFICE.

LOUIS CARRELL STUKENBORG, OF BROWNS, ALABAMA.

HOSE-SUPPORTER.

No. 849,282.

Specification of Letters Patent.

Patented April 2, 1907.

Application filed November 3, 1906. Serial No. 341,851.

To all whom it may concern:

Be it known that I, LOUIS CARRELL STUKENBORG, a citizen of the United States, and a resident of Browns, in the county of Dallas 5 and State of Alabama; have invented a new and Improved Hose-Supporter, of which the following is a full, clear, and exact description.

This invention is an improvement in hose-supporters, having, among other objects, the provision of means to support the hose at diametrically opposite points, especially avoiding the use of metal or other parts that would be uncomfortable to the wearer.

Reference is to be had to the accompanying drawings, forming a part of this specification, in which similar characters of reference indicate corresponding parts in all the figures.

Figure 1 is a perspective view of the supporter complete. Fig. 2 is an edge view of one of the tapes, disclosing the novel manner in which it is folded and secured to form a hook. Fig. 3 is a central sectional view of the same on the line 3-3 of Fig. 4. Fig. 4 is an enlarged side elevation of the same, and Fig. 5 is a central section through one of the short tapes employed for suspending the hose-fastening device.

The invention comprises two tapes 1 and 1^a, preferably of elastic material, made adjustable in length by means of slides 2 and forming loops 3 and 3^a, respectively, at one end of each of the tapes. The tape 1 is permanently connected to the tape 1^a by a cord or other flexible member 4 passing through the loop 3 and between the overlapped end of the tape 1^a. The opposite end of the tape 1 is folded upon itself and then doubled over and secured by one or more rows of stitching, forming it into a soft flexible hooked member. This stitching, as shown, is inclined rearwardly from both the top and bottom of the tape, bringing it to a point 5 at its center. A cord or other flexible member 4^a of the same construction as the member 4 passes through the loop 3^a of the tape 1^a and is adapted to be detachably connected with the doubled or hooked end of the tape 1, as illustrated in Fig. 1. The free ends of the cords 4 and 4^a are passed between the looped ends of short depending tapes 6, where they are secured by means of rows of stitching 7 passing through them, as best shown in Fig. 5.

Suspended in the lower ends of the tapes 6, which are looped over to receive them, are hooks or other suitable means 8 for attaching the supporter to the hose. It is apparent from this construction that the use of metal parts as hooks and the like that would bite into the flesh of the wearer and be a source of discomfort have been avoided. The point 5 of the stitching engages the cord 4^a when the supporter is in use and prevents said cord from shifting sidewise.

My invention presents the advantages that it provides two supports, one on each side, does not drag on the leg, as in the case of a single support on one side, has no metal parts (except the fasteners which rest on the sock) to irritate the leg when the supporter is used in connection with knee-drawers, and keeps the sock smooth and tight around the leg, ankle, and foot.

Having thus described my invention, I claim as new and desire to secure by Letters Patent—

1. A hose-supporter comprising a tape having one end doubled over and secured to form a hook, and means for supporting the hose attached to the other end of said tape and adapted to be engaged with said hook.

2. A hose-supporter comprising a tape having one end doubled over and stitched to a point forming a hook, and means for supporting the hose attached to the other end of said tape and adapted to be engaged with said hook.

3. A hose-supporter comprising two tapes, and cords connecting said tapes together at diametrically opposite points, one of said tapes being doubled over and secured to form a flexible hook whereby one of said cords may be detachably connected therewith.

4. A hose-supporter comprising a plurality of tapes, and hose-supporting devices attached to said tapes, one of said tapes being formed with a soft, flexible hook, whereby the adjacent supporting device may be detachably connected therewith.

In testimony whereof I have signed my name to this specification in the presence of two subscribing witnesses.

LOUIS CARRELL STUKENBORG.
